UNITED STATES PATENT OFFICE

2,001,907

TREATMENT OF MOTOR FUEL

Vladimir Ipatieff, Chicago, Ill., assignor to Universal Oil Products Company, Chicago, Ill., a corporation of Delaware

Application October 26, 1932, Serial No. 639,618

2 Claims. (Cl. 196—10)

This invention relates to the treatment of motor fuel and refers more particularly to the treatment of gasolines produced in the normal or straight run distillation of crude petroleums though similar hydrocarbon fractions produced as a result of the pyrolysis of heavy hydrocarbons or from other sources may also be treated.

More specifically, the invention is concerned with a process for increasing the quality of gasolines in respect to their anti-knock value, though other desirable refining effects in the direction of improved color and gum content are concurrently produced. To effect these desirable objects use is made of both decomposition and synthetic reactions so that the chemical nature of the gasoline is altered.

Owing to the adoption of high compression ratios in automobile engines to increase their thermodynamic efficiency, a demand has been made upon the petroleum refining and other industries which furnish hydrocarbon motor fuels, for fuels of a high anti-knocking or slow burning character.

According to the process of the present invention gasolines produced either by straight distilling methods or by cracking operations upon relatively high boiling oils are subjected first to a controlled pyrolysis which is followed by a step in which certain of the products of the pyrolysis are caused to enter into new chemical combinations which produce compounds of higher anti-knock value and conserve to a large extent the gaseous products of the cracking reactions. Other incidental improvements will be mentioned as the invention is described in detail.

In one specific embodiment the invention comprises first cracking gasoline hydrocarbon fractions to increase the content of olefinic and cyclic hydrocarbons and then causing the chemical combination of olefins and the other hydrocarbon products particularly the gaseous products produced by cracking in the presence of sulphuric acid.

It is recognized that the cracking or so called "reforming" of gasolines to increase their anti-knock value is already known in the art. However, in such operations there must always be an economic balance between the loss of suitable boiling range material and the increased value of the product from an anti-knock standpoint.

According to the present invention it is still economical to subject gasolines to such intensive conditions of cracking as, for example, temperatures of 975 to 1050° F., since a large portion of the olefins which are ordinarily lost in the gases or treated out of the liquid fractions to insure their stability, are utilized to form new compounds with the aromatic and other reactive cyclic hydrocarbons.

The reactions involved when olefins are reacted with cyclic hydrocarbons according to the second stage of the treatment are essentially similar to those between olefins and aromatics and as a typical example of this type of reaction those which occur between propylene and benzol in the presence of sulphuric acid at moderately low temperatures may be cited. While such relatively low temperatures such as, for example 0° C., may be desirable and a part of the invention, temperatures on either side of this point may be employed according to the results desired. Temperatures which have been employed in some cases with good results are comprised within the approximate range of -40° C. to +10° C. When gaseous propylene is passed into a well stirred mixture of benzol and concentrated sulphuric acid in proper proportions, the main product is mono-iso-propyl benzol according to the following reaction:

These may be also produced concurrently a limited yield of di-iso-propyl benzol according to the following equation:

It has been found that such alkylated derivatives of aromatics and other reactive hydrocarbons have consistently higher anti-knock value than the original hydrocarbon, the values obtained in the derivatives being of the order of 50% higher than the original and many times still higher. The mixed character of gasoline hydrocarbons and also the variations in composition and proportion of the olefins in both gases and liquid produced in their cracking according to the first stage of the process precludes any

statement as to the absolute rules governing the interaction of these hydrocarbons in the presence of sulphuric acid. However, as will be developed in a later description of the process and the numerical data, it is evident that combination occurs to a considerable extent and that desirable commercial advantages are obtained by employing the recombination step in conjunction with the cracking or recracking operation according to whether straight run or cracked gasoline is treated.

To assist in describing the nature of the process without limiting its generally broad character the attached drawing has been provided which shows diagrammatically in side elevation an arrangement of suitably interconnected parts in which the essential steps of the process may be conducted. The drawing does not show such obvious and well known expedients as heat exchangers nor any special detail except as the same may be essential to the operation of the process.

Referring to the drawing the plant will be seen to consist essentially of a cracking plant of a type at present used extensively in the art followed by a treating plant in which the olefins and the other hydrocarbon products of the first step of the process are caused to recombine. Gasolines or naphthas may be introduced to the cracking unit through a line 1 containing a control valve 2 and be pumped by pump 3 through a line 4 containing control valve 5 through a tubular heating element 6 disposed to receive heat from a furnace 7. Intermediate insufficiently converted refluxes may be returned by way of line 22 for further decomposing reactions as will be later described. The temperatures and pressures employed in the heating and conversion zones of the cracking unit will depend upon a number of factors among which are the character of the gasoline charged in regard to volatility and chemical composition, the products obtainable by cracking them under different conditions of time, temperature and pressure and the quality desired in the final product. Thus when paraffinic gasolines are employed which yield only limited amounts of high anti-knock gasoline under ordinary cracking conditions, the temperature and pressure may be modified to produce more intensive cracking and increase at the same time the relative amounts of olefins and cyclic hydrocarbons produced. When more readily decomposable gasolines are employed conditions of less severity may be preferable, the object of the cracking process being to produce olefins and hydrocarbons reactive therewith in such amounts and in such proportions that maximum yields of gasoline of a given anti-knock value are possible as a result of the primary and secondary steps.

The products from the heating element may be discharged through a transfer line 8 containing control valve 9 and pass through a well-insulated vaporizing and reaction chamber 10 in which conversion reactions proceed to the establishment of a substantial equilibrium and the total products of the conversion may then be passed through a line 11 containing a control valve 12 into a reduced pressure evaporator 13 which functions principally as a separator for heavy tar fractions unsuited to further heat treatment on account of their coke depositing tendencies, such heavy residuals being removed through line 14 containing control valve 15, and either coked separately or utilized as fuel oil or asphalt stock. As a general rule the amount of these heavy tar fractions is quite small and in some cases the evaporator

may be omitted and the reaction chamber products admitted directly to a fractionator.

Lighter products comprising fixed gases and vapors consisting in turn of liquid of desired boiling range and heavier refluxes may be passed through a line 16 containing a control valve 17 and enter a fractionator 18 of suitable design and capacity for effecting efficient segregation of recycle refluxes from gaseous and gasoline hydrocarbons. The recycle stocks may be taken from the bottom of the fractionator through line 19 containing control valve 20 and pumped by pump 21 through line 22 and valve 23 to line 4 as already mentioned. The amount of reflux thus returned will to some extent determine the character of the conversion step.

Fixed gases and light hydrocarbon vapors may pass through a vapor line 24 containing control valve 25 and the liquids condensed during their passage through a condenser 28, the cooled liquids and fixed gases passing together through rundown line 29 and a control valve 30 to a receiver 31. Line 26 containing control valve 27 typifies any line or combination of lines which may be employed to take off one or a number of side cuts concurrently with the overhead stock and produce a distillate of varying character. In receiver 31 gases and liquids separate and such portions of either as are not to be employed in the final recombining or synthesizing step may be withdrawn through line 32 containing control valve 33 and line 34 containing control valve 35 respectively.

In the second step of the process the olefins and other groups of hydrocarbons are recombined in suitable proportions through the agency of sulphuric acid to produce increase in yield and anti-knock value of gasoline fractions. Of the three groups of hydrocarbons other than olefins to-wit; aromatics, naphthenes and paraffins, which are present, their reactivity with olefins to form "alkylated" derivatives with olefins diminishes generally in the order given. However, the exact course of the reactions cannot be followed exactly and there is evidence to indicate that even with paraffins there is some combination, possibly due to the presence of compounds of isomeric or condensed structure. To utilize the olefinic content of the gases produced they are withdrawn in proper amount from receiver 31 through a line 36 containing control valve 37 by a pump or blower 38 discharged through a line 39 containing a control valve 40 into the upper part of a reactor 54. At the same time the proper amount of condensed liquid as determined by tests is taken from the receiver through line 41 containing control valve 42 and discharged by a pump 43 through a line 44 containing a control valve 45 into line 49 where it comes in contact with a stream of sulphuric acid commonly of 93% strength (though acids of from 80 to 98% may be used), the acid being furnished by a pump 48 which takes suction upon the source of supply not shown through line 46 and valve 47 and discharges the acid through line 49 and valve 50. Obviously other alternative modes of transferring acid may be employed such as blow cases and elevated tanks. The amount of acid necessary for producing best results will usually range from 5 to 10% by volume of the liquid hydrocarbons undergoing reaction. As a general rule there is a given quantity and strength representing a total amount of 100% acid below which the acid is consumed in sulfonating reactions and very little of the desired alkylating of the gasoline hydro-

carbons is effected. With a sufficient amount of acid the sulfonated products remaining dissolved in the acid do not contaminate the hydrocarbon product nor interfere with the functioning of the acid through dilution.

In reactor 54, which represents one of several forms of equipment which may be employed in effecting the synthetic reactions, the liquid hydrocarbons and acid may be forced under pressure through an atomizing or spraying device 51 so that the finely divided liquids fall in the form of a fine mist through the gases, intimate contact and thorough reaction being thus assured. The reactor may contain perforated plates or baffles indicated by 52 and 53 for further breaking up the acid and oil into fine streams after the coalescence following the first atomizing. There is a tendency toward increased temperature in the reactor due to the exothermic character of the reactions and cooling means may be employed either in the reactor or immediately subsequent thereto to retard the progress of undesirable side reactions and favor the combination of the olefins with the cyclic and other hydrocarbons rather than their polymerization among themselves, though this cannot be entirely avoided even under the best of circumstances. However, gums and resins and similar high boiling polymers are seldom encountered in this stage of the process, which indicates that polymerization insofar as it occurs proceeds mainly to the formation of dimers and trimers which have boiling points lying within the range desired in the finished gasoline. The liquid products of the reaction comprising what may be termed "alkylated" hydrocarbons, polymers, unchanged oil and partly spent acid may be passed to a separator 57 through a line 55 containing control valve 56, wherein residual gases devoid of olefins separate in space 58, hydrocarbon liquids in space 59 and spent acid in space 60, the latter being drawn off through a line 74 containing a valve 75 and either discarded or returned for further use after suitable regenerating steps. The gases may be drawn off and vented by way of line 63, valve 64, line 65 and valve 66, a line 61 containing a control valve 62 leading from reactor 54 so that gases may also be withdrawn from this element as may be necessary or desirable.

The final hydrocarbon composite from the process which consists of gasoline having improved anti-knock characteristics may be continuously withdrawn from the separator through line 67 containing control valve 68 to a receiver 69 having a gas release line 70 containing a control valve 71 and a liquid draw line 72 containing a control valve 73. The product usually requires neutralizing and washing according to established procedure following sulphuric acid treatments and may require redistillation to eliminate hydrocarbon fractions boiling above the end point desired in the gasoline. The redistilling step is usually necessary even though previous operations have been directed toward the production of a relatively light gasoline fraction since the synthetic reactions resulting in the fixation of alkyl residues on the reactive gasoline hydrocarbons results in the formation of a certain percentage of what may be termed "alkylated compounds" of high boiling point. These products may be returned to the cracking unit if desired and reconverted in order to conserve the yield.

As an example of the results obtainable in the direction of improved yields and quality of gasoline by the use of the present process the fol-

lowing results are cited. Pennsylvania straight run gasoline having the following properties may be treated:

Gravity—A. P. I.	64.6	5
100 cc. A. S. T. M. distillation—		
I. B. P.—°F	106	
10%	154	
20	186	
50	242	10
90	328	
E. P.	386	
Recovery	percent	96.5
Reid vapor pressure at 100° F	lbs.	8.0
Octane number		50
		15

This gasoline may be first cracked under a pressure of 400 pounds per square inch while utilizing a temperature of 1000° F. at the exit of the heating coil. There may be produced by this operation a number of products according to the yields and properties shown in the following table:

Results of primary or cracking step

Unstabilized gasoline, 85 A.	25
P. I. gravity	85% by volume
Heavy tar, about 5 to 10° A. P.	
I.	1.5% by volume
Fixed gases, 1.23 specific gravity	30
	475 cu. ft./bbl. of gasoline cracked.

The gas produced from the process may have the following composition:

Analysis of gas from cracking

	Percent
Hydrogen	8
Methane	19 40
Ethane	14
Ethylene	9
Propane	7
Propylene	23
Butane and isobutane	2 45
Butylenes	10
Pentanes	6
Amylenes	2

The unstabilized gasoline upon removal of dissolved propane and propylene and a sufficient quantity of the butanes and butylenes to obtain the required vapor pressure may yield a product having the following properties in an amount equal to 76.5% by weight of the original gasoline charged.

Properties of stabilized gasoline

Gravity—A. P. I.	63.6	60
100 c. c. A. S. T. M. distillation—		
I. B. P.—°F	94	
10%	121	
20	144	
50	216	65
90	327	
E. P.	376	
Reid vapor pressure at 100° F	lbs.	9.5
Octane number		75

The combined gaseous products from the cracking operation and the stabilization of the gasoline line may be recontacted with the stabilized gasoline at a pressure of 100 pounds per square inch in the presence of 10% by volume of 90% sulphuric acid. There may be produced by this op-

70
75

eration a yield of stabilized gasoline equivalent to 84% of the original gasoline treated and having the following properties:

5 Gravity—A. P. I.	68.0
Initial boiling point—°F.	95°
10% over at	120°
50% over at	240°
90% over at	340°
10 End point	400°
10 Reid vapor pressure at 100° F.—lbs.	9
Octane number.	85

15 The economic value of this method of operation is sufficiently obvious from a comparison of the yields and quality of product with and without the use of the supplementary recombining or synthetic step. Owing to the fact that the primary cracked gasoline has received a sulphuric acid treatment incidental to its alkylation, the 20 final product is stable in respect to gum and color development on storage and ordinarily requires no further treatment.

25 While the partly spent acid from the alkylation step has been designated as "sludge acid", it should not be considered in the same light as the waste refinery products to which this term is customarily applied since the acid used may be employed for a large number of treatments before its efficiency is diminished to an impractical 30 degree. When the acid becomes saturated with soluble products of an ester character it may be hydrolyzed by treatment with water or steam and a number of by-products recovered such as iso- 35 alcohol and further yields of hydrocarbons. The actual consumption of acid per gallon of finished

gasoline produced is approximately in line with that ordinarily employed in treating cracked naphthas.

The foregoing specification and numerical data presented are sufficient to define the character of the invention and show its merits but neither is to be considered as imposing undue limitations upon its generally broad scope.

5 I claim as my invention:

1. A process for increasing the anti-knock value 10 of light hydrocarbon distillates containing a substantial quantity of hydrocarbons within the gasoline boiling range, which comprises reforming the distillate by pyrolytic conversion thereby 15 forming condensable aromatics and gaseous olefins, reacting such olefins and aromatics in the presence of sulphuric acid to form alkylated derivatives, and recovering a liquid product containing said derivatives.

2. A process for increasing the anti-knock value 20 of light hydrocarbon distillates containing a substantial quantity of hydrocarbons within the gasoline boiling range, which comprises reforming the distillate by pyrolytic conversion thereby 25 forming condensable aromatics and gaseous olefins, condensing the vapors and separating the resultant condensate from the gases, contacting at least a portion of the gases with the condensate 30 in the presence of sulphuric acid and reacting olefins contained in the gases with aromatics contained in the condensate to form alkylated derivatives, and recovering as the product of the process the alkylated condensate thus formed.

VLADIMIR IPATIEFF. 35
